UNITED STATES PATENT OFFICE.

ALFRED B. DISHMAN, OF OKMULGEE, OKLAHOMA.

PENCIL-VENDING MACHINE.

Application filed November 8, 1926. Serial No. 147,011.

The invention relates to pencil vending machines and has for its object to provide a pencil vending machine, coin controlled and provided with means whereby upon the insertion of a coin in the machine a pencil will be released therefrom.

A further object is to provide a pencil vending machine comprising a swinging pencil carrying frame and coin control means which normally locks and holds the free end of the frame against movement and in which a coin is received for releasing the free end of the frame and allowing the frame to swing to a position where a pencil will be discharged therefrom.

A further object is to form the pencil receiving frame from vertically disposed channeled members, in which the ends of pencils are received and held by engagement with a stationary member below the frame, locking means for preventing swinging of the frame and coin controlled means for releasing the free end of the frame and allowing the same to swing over a discharge opening for discharging a pencil therefrom. Also to provide stationary flanges positioned above the discharge opening and where they will pass between adjacent pencils during the swinging operation of the frame before the free end of the frame is over the discharge opening, thereby limiting the number of pencils discharged from the machine. The flanges are proportioned whereby when the frame is in normal inoperative position they are out of the path of the pencils, thereby allowing the pencils to feed downwardly against stops for positioning the pencils for the next operation.

A further object is to provide in combination with the free end of a pivoted frame of a vending machine coin controlled means comprising a stationary member having a pivoted lever, one end of which cooperates with a shoulder of a slidable plate, which plate carries a coin receiving hopper, and which lever is provided with an arm underlying the coin receiving hopper and against which a coin engages for tilting the lever for releasing the plate and allowing inward movement of the hopper and plate and to which hopper is connected the free end of the frame. Also to extend the shaft on which the pivoted lever is mounted through an elongated slot in the plate thereby allowing freedom of movement of the plate.

A further object is to provide adjacent

plates of a coin controlled mechanism with connecting lugs having notches in which notches the coin hopper plate is slidably mounted. Also to provide spring means for returning the hopper and plate to normal locked position after an operation thereof.

A further object is to provide one side of the hopper with a flange in a parallel plane and provided with an L-shaped slot in which a headed member carried by the free end of the frame is received, thereby forming a detachable connection between the free end of the frame and the movable part of the coin control mechanism.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a perspective view of the pencil vending machine.

Figure 2 is a vertical transverse sectional view through the vending machine taken on line 2—2 of Figure 1.

Figure 3 is a perspective view of the coin control mechanism and the pivoted frame.

Figure 4 is a side elevation of the coin control mechanism.

Figure 5 is a top plan view of the coin control mechanism.

Figure 6 is a vertical transverse sectional view through the coin control mechanism taken on line 6—6 of Figure 5.

Figure 7 is a vertical longitudinal sectional view taken on line 7—7 of Figure 5.

Referring to the drawings, the numeral 1 designates the casing of the machine and 2 the closure preferably for the rear side thereof, which may be of any construction and locked in any desired manner, however for purposes of illustration a conventional form of lock 3 is shown. The front side of the casing 1 is provided with a sight opening 4, through which opening pencils 5 within the machine may be seen by the purchaser.

Pivotedly mounted within the casing 1 on the pins 6 is a vertically disposed pencil receiving frame 7, and which frame is formed from angle members 8 which form the pencil receiving channels 9, in which the ends of the

5 pencils 5 are received. Angle members 8 have their flanges secured together by means of rivets 10, thereby forming a rigid structure for supporting a plurality of pencils, 5 which pencils during the filling of the frame are placed therein through the upper open ends 11 of the channels. The opposite sides of the frame are braced in relation to each other by means of the connecting bars 12, 10 therefore it will be seen that both sides of the frame will move inwardly and outwardly simultaneously. Secured to the inner sides of the casing 1 by means of screws 13 are plates 14, one of said plates being provided 15 with a U-shaped portion 15 which receives the removable coin box 16 and connecting the U-shaped member 15 and the other plate 14 is a horizontally disposed angle bar 17 which is disposed beneath the lower end of 20 the pivoted frame 7 and is provided with upwardly struck horizontally disposed arms 18 which support the pencils 5 within the channels 9, and with which the lower pencil 5 has a sliding engagement when the lower 25 end of the frame 7 is swung inwardly. Disposed rearwardly of the member 17 in spaced relation thereto is a vertically disposed plate 19, and between which plate and the angle members 17 pencils are discharged onto the 30 discharge plate 20 where they roll outwardly through the discharge opening 21 into engagement with the upwardly extending flanges 22 and from which position the operator moves the same. Secured to the vertically disposed plate 19 by means of screws 23 which extend through vertically disposed slots 24 therein are adjustable plates 25, the upper ends of which terminate in forwardly extending flanges 26, which flanges 40 terminate adjacent the inner sides of the channels 9 as clearly shown in Figure 2 and in positions where they will enter between adjacent pencils 5 as the frame is swung inwardly, thereby preventing discharge of a predetermined number of pencils, thereby 45 allowing a single or plurality of pencils to be vended at a predetermined price. Angle member 17 is preferably provided with an upwardly inclined spring 27 of the leaf type for partially supporting the pencils, however this may be eliminated if desired.

55 ever this may be eliminated if desired.
The coin control mechanism is preferably entirely supported by one of the plates 14 as shown in Figures 4 to 7 inclusive. Plate 14 referred to is provided with inwardly extending lugs 28 which are preferably welded to the lugs 29 of the plate 30, however for purposes of illustration rivets 31 are shown. Plate 30 is in spaced relation to the plate 14 and in a plane parallel thereto, and is also connected to the plate 14 by means of a shaft 32. Slidably mounted in the recesses 33 in the adjacent sides of the lugs 29 and 28 is a vertically disposed plate 34, which plate has a recess 35 and a plurality of shoulders

36, and with which shoulders a flange 37 carried by the lever 38 cooperates for locking the plate 34 against inward movement until the lever 38 is rocked upwardly at its inner end to a position where the flange 37 thereof will be out of the path of the shoulders 36. Lever 38 is rocked downwardly at its outer end by the weight of a coin engaging the horizontally disposed flange 39 thereof. Plate 34 is provided with an elongated aperture 40 through which the shaft 32 extends, therefore it will be seen that the pivoted lever 38 which is rockably mounted on the shaft 32 will remain stationary as far as the pivotal point is concerned when the plate 34 is moved inwardly. It will also be noted that the weight of the inner end of the pivoted lever 38 will move said end downwardly to latching position when the plate 34 is moved outwardly. Plate 34, at its forward end is provided with a vertically and right angularly disposed flange 41, which carries the coin hopper 42 to one side of the plate 30, and into which hopper a coin is discharged through the coin slot 43 of the casing 1 and is conveyed downwardly over the plate 44 as shown in full and dotted lines in Figure 4 to a position where it will engage the flange 39 of the lever 38, which flange underlies the hopper 42, and its weight will rock the lever 38 for releasing the plate 34, thereby allowing the plate 34 as well as the hopper 42 to move inwardly, and as the flange 39 does not move, it is obvious the coin will be released from the hopper as the hopper is moved inwardly and will drop into the removable coin receiving box 45 disposed below the same. Slugs and coins which are not of the proper size or weight will be discharged into the coin box 45 through the opening 46, however the plate 14 is provided with a slotted U-shaped member 47 having its slot 48 in registration with the coin entrance of the hopper for limiting the size of a coin, that is the diameter, that may be inserted in the device. In operation, the operator drops the coin in the chute 43 and it passes through an operation and mechanism as above set forth; then the operator places his finger against the member 49, forces the same inwardly, and as said member is carried by the plate 41, the hopper and the plate 34 are forced inwardly. Plate 41 is provided with an inwardly extending flange 50 having an L-shaped slot 51 therein, and in which L-shaped slot, that is the vertically disposed portion 52 thereof, the headed lug 53, which is carried by the lower end of the frame 7 at one side thereof, is disposed. It will be seen that as the hopper and the flange 50 are forced inwardly, the lower end of the frame 7 will also move inwardly to a position where the lower pencil 5 will be discharged therefrom. To return the hopper and plate 34 to normal position a coiled

spring 54 is provided, which coiled spring is connected at 55 to an arm 56 carried by the inner end of the plate 34 and is anchored at 57 to the forward side of the casing 1, therefore it will be seen that the removable parts, after an operation of the device, will be immediately returned to normal locked position. By providing the shoulders 36 in stepped relation to each other, it will be seen 10 that the locking operation will immediately start upon the outward return movement of the lower end of the frame 7, thereby preventing a pencil purchaser from allowing partial return of the frame for again forcing 15 the pivoted frame inwardly for delivering pencils without the usual coin control mechanism.

From the above it will be seen that a pencil vending machine is provided which is 20 simple in construction, the parts reduced to a minimum and one which is positive in its operation and which may be cheaply manufactured and sold.

The invention having been set forth what 25 is claimed as new and useful is:—

1. The combination with the free end of a discharge frame of a vending machine, of coin control mechanism for said free end, said mechanism comprising a coin receiving 30 hopper, a plate to one side of said coin receiving hopper and having a recess therein, said plate being slidably mounted and supporting the hopper, a fixed shaft extending through an elongated aperture in the 35 plate, a pivoted lever mounted on said shaft, a flange carried by said lever and disposed in the recess of the plate, shoulders within the recess of the plate and with which said flange cooperates, a coin engaging flange carried by the other end of the lever and underlying the coin hopper, said hopper and plate being simultaneously movable inwardly and outwardly.

2. A coin controlled mechanism comprising 45 a plate, outwardly struck lugs carried by said plate, an auxiliary plate in spaced relation to the first mentioned plate, members carried by the auxiliary plate and secured to the lugs of the first mentioned plate, a hopper adjacent the auxiliary plate and outside thereof, a spaced plate carried by the hopper and slidably mounted in bearings of the lugs and inwardly extending members, a shaft connecting the first mentioned plate and the auxiliary plate and extending through an elongated aperture in the hopper carried 50 plate, a pivoted lever mounted on the shaft, a locking flange carried by one end of the lever and cooperating with the hopper car-

ried plate adjacent one end thereof, a coin 60 engaging member carried by the other end of the lever and underlying the hopper and means for simultaneously returning said hopper and hopper carried plate to outward position after an inward movement thereof. 65

3. The combination with the free end of a pivoted discharge frame of a vending machine, of a coin control mechanism for said free end, said mechanism comprising a plate carried by one side of the frame in off-set 70 relation and movable therewith, a stationary plate to one side of the frame and in which the first mentioned plate is slidably mounted, a hopper carried by the first mentioned plate and movable therewith, and a coin controlled 75 pivoted latching member carried by the stationary plate and extending into the hopper.

4. The combination with the free end of a pivoted discharge frame of a vending machine, of coin control mechanism for said free end, said mechanism comprising a plate carried by one side of the frame in offset 80 relation and movable therewith, a hopper carried by the plate between the plate and the frame, a stationary plate, the first mentioned plate being slidably mounted in the stationary plate, a pivoted detent between the hopper and the slideable plate, said detent being pivotally supported by a pin carried by the stationary plate and extending 85 through an elongated aperture in the slideable plate, an ear carried by said detent and cooperating with a stop carried by the slideable plate and an ear carried by the detent and extending into the hopper in the path 90 of a coin.

5. The combination with the free end of a vending machine frame pivotally mounted, of a coin control mechanism, said mechanism comprising a movable plate rigidly 100 carried by the free end of the frame, a stationary plate, said movable plate being slidably mounted in the stationary plate, a hopper carried by the slideable plate and movable therewith, a detent between the slideable plate and the hopper and forming 105 means for locking said slideable plate against movement, a coin engaging member carried by the detent and extending into the hopper, said detent being supported by a pin carried by the stationary plate and extending through an elongated aperture in the slideable plate and spring means cooperating 110 with the slideable plate for normally forcing the same to inoperative position.

In testimony whereof I hereunto affix my signature.

ALFRED B. DISHMAN.
